UNITED STATES PATENT OFFICE.

HENRY GRADY SWAFFORD, OF SHELBYVILLE, TENNESSEE.

VENDING MACHINE.

Application filed May 25, 1925. Serial No. 32,940.

My invention relates to a vending machine and one of the objects of the invention is to provide a device of this character which is specially adapted for use in vending groceries.

Another object of the invention is to devise a vending machine which may be cheaply constructed, and of a few simple parts that will not easily get out of order.

With these and other objects in view my invention consists of certain novel and peculiar features of construction and combination of parts, as hereinafter more fully described and particularly pointed out in the claim.

Referring to the drawings for a more complete disclosure of the invention:

Fig. 1 is a front elevation with parts of the casing removed to show the operating mechanism;

Fig. 2 is a section on the line 2—2 of Fig. 1;

Fig. 3 is a section on the line 3—3 of Fig. 1;

Fig. 4 is a fragmentary section on the line 4—4 of Fig. 2;

Fig. 5 is a section on the line 5—5 of Fig. 2; and

Fig. 6 is a fragmentary section showing the means for guiding the sprocket chain.

Mounted within and along the median line of the casing 1 of the machine is a rotary sprocket 2 and a similar sprocket 3, connected together by the chain 4 which engages with the teeth on the said sprockets.

At intervals on the said chain are flanges 5, provided with apertures 6 and through these apertures pass screws 7 for engaging and holding shelves on which the goods to be vended are placed. The said shelves are spaced apart a distance equal to the height of the opening 9 in the front of the casing and through which access may be had to the shelf 10. The shelf 11 is disposed in line with the cross-piece 12 so that access cannot be had at the same time to the goods and the shelf 11. The front of the casing is provided with glass windows 13 to afford a view of the contents.

Secured to the shaft 14 and rotatable with the sprocket 3 is a ratchet 15 having teeth 16 which engage with a spring pressed pawl 17. Secured to the pawl 17 is a stud 18 which engages with a spring pressed dog 19, which dog is pivoted to a hand lever 20. The said hand lever is pivoted at its lower

end to the casing and projects through a slot 21 and has a hand grip 22 at its upper end. Spaced around the ratchet 15 are studs 23 for engagement with the sloping face 24 of the dog 19, as will be hereinafter set forth.

Mounted in the front part of the casing is a coin lock for controlling the operation of the vending machine. This comprises a coin chute 25 leading into a coin receptacle 26 which is fixed to the end of a balanced beam 27 supported, by knife edges 28, on the bracket 29. A nut 30 engaging the screw 31 is used for adjusting the beam to accord with the particular weight of the coin to be used for operating the machine. At the other end, the beam 27 is provided with an aperture 32, the said end reciprocating between guides 33 which are provided with aligned apertures 34.

Pivots secured to the hand lever 20 is a pin 35, normally engaging one of the apertures 34 and adapted, when the apertures 34 and 32 are in alinement, to pass through the same.

The coin receptacle 26 is provided with a pivoted side 36 having a cam surface 37 for engagement with the hand lever 20 to release the coin from the coin receptacle.

In order to hold the shelves and sprocket chain in proper position, the body of the chain runs in a groove 38 formed in the partition 39. By this construction, notwithstanding the considerable load on the shelves, they will not readily be thrown out of alinement.

Operation.

Merchandise is from time to time placed on the shelves in the front of the cabinet. When a customer desires an article, a suitably indicated coin is deposited in the coin slot. The nut 30 has been previously adjusted so that when the proper coin is in the coin receptacle 26, the beam will be level, and the aperture 32 therein will be in alinement with the apertures 34. The customer then grasps the hand lever, pulls it forward, thereby releasing the pawl 17 from the ratchet teeth 16, whereupon the loaded shelves will move downward one step, thus making available to the customer the goods on shelf 11. As the ratchet rotates, one of the studs 23 engages the inclined face 24 on the dog 19, thereby disengaging it from the stud 18 and permitting the spring to draw

the pawl 17 backwards to engage the next tooth on the ratchet and stopping its rotation.

As the hand lever is pulled forward it engages the cam surface 37 to open the cover 36, releasing the coin which drops into the box 40.

It will be noted that the hand lever cannot be pulled forward until the apertures 32 and 34 are in alinement, whereby the pin 35 can enter. Unless, therefore, the proper coin, for which the machine is set, has been placed in the chute, the beam will not assume the right position and the apertures will not be in alinement.

For independently opening the cover 36 of the coin box, to release an unsuitable coin which has been placed therein, I may provide a push rod 41.

When the goods on the front shelves are not heavy enough to move downwards on release of the locking means, then suitable weights may be placed on the shelves for this purpose.

From the above description it will be apparent that I have produced a device of the character described, which accomplishes the purpose for which it was intended, and while I have illustrated and described the preferred form of my invention, it will be understood that I reserve the right to all changes, properly falling within the spirit and scope of the appended claim.

Therefore, what I claim as new and desire to secure by Letters Patent is:

In a vending machine, a conveyor, a plurality of supports for goods carried thereby, means for locking the conveyor in position, means for releasing the lock to permit the conveyor to move and comprising an operating lever, a coin-controlled balanced beam having an aperture therein, a pin carried by the said lever and adapted to enter the said aperture when the beam is in a predetermined position to permit the lever to move to release the said lock.

In testimony whereof I affix my signature.

HENRY GRADY SWAFFORD.
